UNITED STATES PATENT OFFICE

160,005

RACKET OR SIMILAR ARTICLE

John F. Myles, Jr., Sherrill, N. Y.

Application January 13, 1948, Serial No. 143,710

Term of patent 3½ years

(Cl. D34—5)

REFERENCES CITED

The following references are of record in the file of this patent:

Simmons Hardware Company (1890) Catalog, page 547, item: meal sieve, Fig. No. C2347.

Lyon & Healy Wholesale Counter Sales Book (1925), page 100, item: The Washburn "Classic" tenor banjo; page 305, item: No. 12-078, professional tambourine.

To all whom it may concern:

Be it known that I, John F. Myles, Jr., a citizen of the United States, residing in Sherrill, county of Oneida, State of New York, have invented a new, original, and ornamental Design for a Racket or Similar Article, of which the following is a specification, reference being had to the accompanying drawings, forming a part thereof, of which:

Fig. 1 is a plan view of the racket or similar article, showing my new design.

Fig. 2 is a side elevation of the racket of Fig. 1.

What I claim is:

The ornamental design for a racket or similar article, substantially as shown.

JOHN F. MYLES, JR.
